UNITED STATES PATENT OFFICE.

WAYNE S. SEARLES, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND.

OPHTHALMIC MOUNTING.

Application filed January 3, 1921. Serial No. 434,684.

This invention relates to improvements in ophthalmic mountings, and has for its object to provide a mounting of this character in which the ends of the bridge member are connected to the end piece of the eye-wire giving greater strength at the point of connection and improving the appearance of the mounting, by which construction it will be seen that the ends are located on the inner edge of the circle adjacent the bridge member instead of on the outer edge at a point diametrically opposite the attaching end of the bridge member as is usually the case.

With these and other objects in view, the invention consists of certain novel features of construction, as will be more fully described, and particularly pointed out in the appended claim.

In the accompanying drawings:

Figure 1 is a rear view of an eyeglass mounting, illustrating my improved construction.

Figure 2 is a greatly enlarged view illustrating one arrangement by which the end of the bridge member is connected to the end piece of the eye-wire.

Figure 3 is another arrangement by which the end of the bridge member is connected to the end piece of the eye-wire.

Figure 4 is a view on line 4—4 of Figure 3 looking down upon the end piece, and illustrating one arrangement by which the bridge member is connected to the eye-wire end piece.

With reference to the drawings, 10 designates the eye-wire which is usually formed of metal and provided at its opposite ends with end pieces 11 through which the ends of the wire are secured together by means of a binding screw 12.

In my improved construction these end pieces are provided with the usual shoe portions 13 which embrace the eye-wire, as best illustrated in Figure 4, the end pieces 11 extending rearwardly so as to be partially hidden by the rim from the front of the mounting.

My improved construction contemplates the positioning of these end pieces at the inner edge of the wire or at a point adjacent

the ends of the bridge 14 and it is found in practice by connecting the ends of the bridge to the end pieces of the eye-wire that a much stronger connection is made than as though the bridge ends were connected directly to the eye-wire independently of the end pieces; then again by so positioning these end pieces adjacent the ends of the bridge member the whole joint is made much less conspicuous from the front of the mounting, which is a feature much desired in mountings of this character.

By my improved construction the usual non-metallic or shell rim 15 may be readily applied leaving a continuous surface all around the eye-wire except where the end portions of the non-metallic rim abut against the end piece of the metal rim and partially conceal the end piece.

The ends 16 of this non-metallic rim may be secured by rivets as at 17 or any other fastening means may be employed.

The device is extremely simple and practical in construction and by its use the strength of the mounting may be greatly increased at that place which is ordinarily its weakest point.

The foregoing description is directed solely towards the construction illustrated, but I desire it to be understood that I reserve the privilege of resorting to all the mechanical changes to which the device is susceptible, the invention being defined and limited only by the terms of the appended claim.

I claim:

In an ophthalmic mounting, the combination of metallic rims for the lenses of eyeglasses, the opposite separable ends of which are located at the inner edges of the rims, each of said rim ends being provided with a perforated projection extending wholly to the rear, a screw for securing the projections of each rim together, a non-metallic rim about each metallic rim with its ends abutting said projections, a fingerpiece bearing portion connected to one of each pair of projections, and bridge ends connected to said projections through said bearing portion.

In testimony whereof I affix my signature.

WAYNE S. SEARLES.
